[57] CLAIM

The ornamental design for a water ski rope handle, as shown and described.

DESCRIPTION

FIG. 1 is a plan view of a water ski rope handle embodying my new design, the bottom view being a mirror image of the same,

FIG. 2 is a right end elevation view of the water ski rope handle of FIG. 1, the left end elevation view being a mirror image of the same,

FIG. 3 is a front elevation view of the water ski rope handle of FIG. 1,

FIG. 4 is a rear elevation view of the water ski rope handle of FIG. 1, and,

FIG. 5 is a perspective view of the water ski rope handle.
